[57] CLAIM

The ornamental design for a combined writing pen and cigarette lighter, as shown and described.

DESCRIPTION

FIG. 1 is a perspective view of a combined writing pen and cigarette lighter showing our new design;

FIG. 2 is a perspective view thereof with the cap in the open position;

FIG. 3 is a left side elevational view of FIG. 1;

FIG. 4 is a front elevational view of FIG. 1;

FIG. 5 is a rear elevational view of FIG. 1;

FIG. 6 is a top plan view thereof;

FIG. 7 is a bottom plan view thereof;

FIG. 8 is a left side elevational view of FIG. 2;

FIG. 9 is a front elevational view of FIG. 2;

FIG. 10 is a rear elevational view of FIG. 2;

FIG. 11 is a top plan view thereof; and

FIG. 12 is a bottom plan view thereof.
